ATTORNEY.

UNITED STATES PATENT OFFICE.

DAVID S. WILLIAMS, OF LOS ANGELES, CALIFORNIA.

CAR-DOOR FASTENER.

1,294,009.

Specification of Letters Patent. Patented Feb. 11, 1919.

Application filed May 27, 1918. Serial No. 236,671.

To all whom it may concern:

Be it known that I, DAVID S. WILLIAMS, a citizen of the United States, residing at Los Angeles, in the county of Los Angeles and State of California, have invented a new and useful Car-Door Fastener, of which the following is a specification.

This invention relates to a car door fastener and particularly pertains to a means for locking the sliding doors of freight cars. It is the object of this invention to provide a car door and a fastener therefor so constructed that the car door cannot be pried open and access gained to the interior 15 of the car without breaking a seal.

Another object is to provide a fastener adapted, when in its locking position, to have a wedge action and serve to tightly hold the door in its closed position against 20 vibration.

Another object is to provide a sliding door latch or bolt adapted to be disposed at the rear lower corner of a sliding door and to also provide a keeper co-operating therewith by which the bolt will be automatically thrown into engagement with the keeper on closing of the door from its forward end.

A further object is to provide means whereby the bolt, on being withdrawn from the keeper, will be held in such position to permit the door being open from its forward end and which is adapted to release the bolt on opening of the door to restore it to its 35 normal locking position. Other objects will appear hereinafter.

The invention is illustrated in the accompanying drawings, in which:

Figure 1 is a perspective view illustrating the rear lower portion of a sliding door in a partly open position showing the fastener in its normal position in readiness to be engaged by the keeper on closing of the door.

Fig. 2 is a view of the fastener in side elevation with parts broken away showing it in its locking position in full lines and indicating the unlocked position in dotted lines.

Fig. 3 is a view in section and elevation with parts broken away, as seen on the line 50 3-3 of Fig. 2.

Fig. 4 is a perspective view of the bolt and its locking lever as removed from its casing.

Fig. 5 is a view showing a car door in side elevation in its closed position.

Fig. 6 is an enlarged detail section as seen on the line 6-6 of Fig. 5.

More specifically 7 indicates a car door which is suspended by rollers 8 from an over-head track 9 as is common in freight car construction.

In carrying out my invention a stop or jamb 10 is provided along the forward edge of the door opening against which the door 7 abuts when in its closed position as shown in Figs. 5 and 6. Mounted on the outer face of the jamb 10 is a metallic bar 11 which is adapted to project over the forward edge of the car door 7 throughout the length thereof when the latter is in its closed position so as to close the joint at this point against leakage and also guard against the insertion of tools under the forward edge of the car door by which it might be pried open and, furthermore, prevent the car door from being pried out from its lower edge.

My fastener embodies a keeper 12 comprising a back plate 13, a horizontal shelf 14 formed with a bolt receiving socket or opening 15, an upwardly projecting ledge 16 on the outer edge of the shelf 14 and an inclined runway 17 leading downwardly from the rear edge of the shelf 14. The keeper is designed to be mounted on the car side 18 adjacent to the lower rear corner of the car door as shown in Fig. 5.

Mounted on the rear lower corner of the car door is a plate 19 formed with a rectangular housing 20 arranged to lie against the rear edge of the door 7. This housing receives and forms a guide for a rectangular bolt 21 adapted to slide vertically in the housing and to normally project below the lower edge of the housing and door to engage the keeper 12. The lower end of the bolt is formed with an arcuate forward edge 22 adapted to contact the inclined runway 17 on closing the door and the rear lower portion of the bolt is beveled or inclined at 23 where it engages the rear wall of the opening 15 to act as a wedge in crowding the door forward tightly against the jamb 10. The bolt 21 is gravity operated and its downward movement is limited by a stop 24 on its upper end seated upon the upper edge of the housing 20. Means are pro-

vided for manually lifting the bolt to disengage it from the keeper and also afford means for sealing the bolt in its lowermost position. This means embodies a lever 25 pivoted at 26 between a lug 27 and a flange 28 formed on the rear face of the casing 20. The lever 25 extends along one side of the flange 28 when in its normal vertical position; the flange 28 being of such length 10 and depth as to substantially conform to and cover the side face of the lever 25. The lower portion of the lever 25 extends through the casing 20 and into a slot 29 formed in the bolt 21, the portion of the 15 lever disposed in the slot being formed with cam faces 30 and 31 adapted to engage the upper and lower ends of the slot 29. The cam face 30 engages the upper end of the slot on swinging the lever 25 outwardly to 20 lift the bolt as indicated in dotted lines in Fig. 2 and the cam face 31 engages the lower end of the slot 29 to hold the bolt against upward movement and also serves to force the bolt downwardly to cause its 25 inclined face to bear on the margin of the opening 15 under pressure and thereby effect the desired wedging action. The lever 25 is held in its closed position by a pivoted loop 32 mounted on the casing 20 and is 30 adapted to extend over the upper ends of the lever 25 and the flanges 28 which are turned outwardly to receive it. Openings 33 and 34 are formed in the lever 25 adjacent to its upper end at such point as to 35 be disposed on opposite sides of the loop 32 when the latter is in its engaging position and formed in the flange 28 are openings 35 and 36 adapted to register with the openings 33 and 34. 40 When it is desired to seal the fastener the usual zinc or soft metal ribbon 37 is passed through the openings 33 and 35, and brought back through openings 34 and 36 astride the loop 32 as shown in Fig. 2; the 45 ends of the ribbon being joined by the usual lead seal 38.

In opening the door it is desirable that the bolt on being lifted remain in its uppermost position out of engagement with the 50 keeper so that on disengaging the bolt no further attention to the fastener will be necessary. To effect this result the forward flange of the bolt is formed with a vertical channel 39 adjacent its lower end having an inclined wall 40 and formed on the interior of the casing 20 is a lug 41 which projects into the channel 39 and is adapted to engage the inclined face 40 when the bolt is moved to its uppermost position and 55 operating therewith to shift the bolt rearwardly and dispose its lower end above a rib 42 extending along the rear margin of the opening 15. In order to permit the rearward movement of the bolt in its guide casing 60 the rear face of the bolt is guided against

a transverse rib 43 on the inner face of the casing and the bolt is formed with a cut-out portion 44 on its rear face at such point as to be opposite the lug 41 when the bolt is crowded rearwardly by the lug 41.

In the operation of the invention when it is desired to open the door the seal is removed, the loop 32 lifted, and the lever 25 swung downwardly as indicated in dotted lines in Fig. 2. The cam face 30 engaging the upper end of the slot 29 will lift the bolt which, as it nears the terminus of its upward movement, will be crowded rearwardly by the combined action of the lug 41 and inclined face 40 so that the lower end of the bolt will project over the rib 42 as indicated in dotted lines in Fig. 3. On releasing the lever 25 the bolt will then seat on the rib 42 and will be retained in its uppermost position. The door may then be moved toward its open position whereupon the bolt will ride from the rib 42 onto the shelf 14 and down the incline 17, the bolt gravitating to its normal lowermost position when clear of the incline. The bolt moving downwardly engages the cam face 30 and swings the lever 25 back to its vertical position. If desired the bolt may be reengaged by a second keeper in order to retain the door in its open position.

In closing the door, the lower end of the bolt will ride up the incline 17 and into the opening 15 thus automatically latching the door. The inclined face 28 engaging the rear edge of the opening 15 will crowd the door forwardly and the bolt and keeper are so arranged relative to the forward edge of the door and the jamb 10 that when the door abuts lightly against the jamb the bolt will be near its lowermost position so that it will be necessary to force it downwardly by pressing the lever 25 inwardly thus causing the door to be tightly wedged against the jamb 10.

As a further means of holding the door against vibration a horizontal rib 45 is formed on the lower edge of the plate 19 and has an inclined face 46 adapted to wedge against the inner face of the flange 16 on the keeper when the door is in its closed position so as to crowd the door inwardly at its rearward end. This flange also serves to guide the rear edge of the door and the bolt to their locking position.

I claim:

1. In a sliding car door fastener, a vertically slidable bolt having an inclined side face adjacent its lower end, a keeper having an opening one margin of which is adapted to be engaged by the inclined face on the bolt, a guide housing incasing said bolt, a flange on said housing, a lever pivoted on said flange to extend parallel therewith, a cam face on said lever engageable with the bolt and adapted to force the inclined face 120

of the bolt against the edge of the opening in the keeper, and means for holding the lever in its uppermost position.

2. In a sliding car door fastener, a vertically slideable bolt having an inclined side face adjacent to its lower end, a keeper having an opening one margin of which is adapted to be engaged by the inclined face on the bolt, a guide housing incasing said bolt, a flange on said housing, a lever pivoted on said flange to extend parallel therewith, a cam face on said lever engageable with the bolt and adapted to force the inclined face of the bolt against the edge of the opening in the keeper, and a second cam face on said lever engageable with the bolt for lifting same on downward movement of the lever, and means on the bolt and housing for

shifting the bolt to one side at the terminus of its upward movement whereby it may be seated on the edge of the keeper opening.

3. In a sliding door fastener, a keeper, a bolt engageable therewith, and a lever slidably connected with the bolt and having an inclined face for exerting a wedge action on said bolt.

4. In a sliding door fastener, a keeper, a bolt engageable therewith, said bolt engageable with said keeper to exert a wedge action thereon, and a lever slidably connected with the bolt and having an inclined face for exerting a wedge action on said bolt coöperating with the inclined face on the bolt to advance the bolt laterally in relation to the keeper.

DAVID S. WILLIAMS.
